R. C. Murch.

Excavator

Nº 12,514.

Patented Mar. 13, 1855.

UNITED STATES PATENT OFFICE.

ROBERT C. MAUCK, OF HARRISONBURG, VIRGINIA.

DITCHING-MACHINE.

Specification of Letters Patent No. 12,514, dated March 13, 1855.

To all whom it may concern:

Be it known that I, ROBERT C. MAUCK, of Harrisonburg, in the county of Rockingham and State of Virginia, have invented a new and useful Improvement in Ditching-Machines; and I do hereby declare that the following is a full, clear, and exact description of the construction and operation of the same, reference being had to the annexed 10 drawing, forming part of this specification, in which—

Figure 1 is a top view of the machine. Fig. 2, is a vertical longitudinal section. Fig. 3 is an elevation of rear end.

15 Similar characters of reference in the several figures denote the same part of the machine.

The nature of my invention consists in constructing the machine with the plow or 20 cutter suspended as will be described, from the front of a horizontal frame, and resting on its heels; the rear of the frame supported by an inclined standard frame, swung to the longitudinal frame, and carrying a roller 25 in its lower extremity, so that the machine will rest on said roller and the heels of the plow or cutter; a rack and pinion connecting the two frames producing the elevation or depression of the cutting edge of the plow, 30 by turning it around its heels as will be set forth; the excavated earth being carried up and from the machine by endless conveyers, arranged as will be described.

The invention further consists in the 35 employment of an inclined trimming cutter arranged and operating as will be set forth.

The construction and operation of my machine will be readily understood from the 40 following description and reference to the drawing, in which A is the horizontal frame composed of longitudinal pieces a, connected by cross pieces; this frame is connected with the plow or cutter B by the pendant braces c and d and by the attachment of the inclined side pieces E to the said frame, as 45 shown in the drawing. The inclined cutter B is held between the cheek plates e, upon the heels f of which the forward part of the machine rests. The rear of the horizontal 50 frame A is connected with the standard frame F by a rod i passing through both frames, or in any suitable manner so that the standard frame may swing from the frame A.

55 At the lower portion of this frame F is the roller G, which by resting on the ground

as shown in Fig. 2 causes the entire machine to be supported on said roller and the heels f of the cheeks e. The rack g secured to the swinging frame F, meshes in the pinion h on the shaft k, which is journaled on the frame A, so that by the turning of said shaft the swinging frame F can be more or less inclined to the surface of the ground. Between the cheeks e and side pieces E are 60 rollers H and I over which passes the endless conveyer K, which may be of chains and iron slats or of any known construction. Motion is communicated to this conveyer from the roller G by means of bands l and l' as 65 shown in Fig. 2. Under the head of conveyer K, and resting transversely on frame A is the conveyer J which is moved by the weight of the earth falling upon it so that the product of the excavation is deposited 70 on one side of the ditch.

The pendant braces c are beveled on their inner front edges, and flare slightly outward so as to make the opening sufficiently wide for the passage of the rear portion of 80 the machine without jamming. I design however to construct the cheeks e so as to sweep outward toward the front, and reduce the width of the back edge of the scraper compared with the distance between 85 the sides E so that the earth in passing up the passage between them, upon the conveyer K may not rub against the sides E. The cutting edge of the scraper is shown as being straight, though I design to have 90 a triangular plate with vertex to the front placed under the cheeks e, and projecting before the present edge, for facilitating the operation of the machine. These and many other minor modifications may be made on 95 the machine as here described without altering the principles upon which I base my claims.

The operation of my machine is as follows: The shaft k is first turned so as to 100 give the cutter the requisite inclination, raising the heels of the cheeks e from the ground and causing the edge n to rest on the ground. The matter of inclination of the cutter depending on the nature of the earth, and 105 other circumstances well known to persons acquainted with ditching, need not be minutely dwelt upon here: the point being the construction of the machine as here described so that the movement of the swinging frame F regulates the inclination. The 110 machine is drawn forward by animals suit-

ably attached, causing the result of the excavation to pass between the cheeks and on to the conveyer K, which carries it upward and drops it over its head upon the carrier 5 J from which it passes to the ground outside of the ditch, the gravity of the load producing the motion of the said transverse carrier. This carrier is so connected with frame A that it may be made to run 10 to either side of the ditch on which it may be desired to deposit the earth. When after repeated cuts the ditch becomes too deep to turn the machine without taking it out; when the extremity is reached, the rack g 15 is so moved as to carry the frame E to the rear, and elevating the cutting edge n cause the fore part of the machine to rest on the heels f as at first. The machine is then driven out and turned, and is then prepared 20 for cutting as before.

In front of the cutter is the trimming blade P, secured in the frame A by wedges or any other suitable means, and inclining from the bottom upward. The frame A 25 may be arranged to accommodate the knife adjusted to two or more widths of ditch.

Its use is as follows: When the ditch is finished as regards depth, the cutter is elevated from the surface as above specified and the machine driven forward, trimming the sides of the ditch so as to incline from bottom upward. The earth which falls is caught on the cutter and carried off in the usual manner. The trimmer is of coarse removed during the horizontal cutting. 30 35

Having thus described my invention and the operation of the same, what I claim as my invention and desire to secure by Letters Patent, is—

The herein described mode of regulating 40 the operation of the cutter or plow by means of the swinging frame E, connected with the body of the machine substantially as specified, in connection with the cheek plates e, operating as, and for the purposes set forth. 45

In testimony whereof, I have hereunto signed my name before two subscribing witnesses.

R. C. MAUCK.
